UNITED STATES PATENT OFFICE.

WILLIAM D. WIDDERS, DECEASED, LATE OF EXETER, MISSOURI, BY GATSIE H. WIDDERS, WIDOW, OF EXETER, MISSOURI.

TRAIN-PIPE COUPLING.

1,102,827.

Specification of Letters Patent.

Patented July 7, 1914.

Application filed January 3, 1913. Serial No. 669,279.

To all whom it may concern:

Be it known that WILLIAM D. WIDDERS, deceased, late a citizen of the United States of America, residing at Exeter, in the county of Barry and State of Missouri, did invent new and useful Improvements in Train-Pipe Couplings, set forth in the annexed specification.

This invention relates to coupling devices and more particularly to that type of devices which are adapted to connect the air, steam and signal hose in train systems.

The object of the invention is the provision of a simple and efficient device for connecting simultaneously and automatically with the car couplers, the air, steam and signal hose.

A further object of the invention is the provision of a simple and efficient means of this character which is adapted to automatically connect the air, steam, and signal hose of train systems simultaneously with the connection of the car couplers and to accommodate itself to all variations in the 25 relative position of the connected cars.

Further objects of this invention will appear as the following specific description is read in connection with the accompanying drawings, which form a part of this application, and in which:

Figure 1 is a side elevation with certain parts omitted. Fig. 2 is a top plan view. Fig. 3 is a similar view to Fig. 1 with parts shown in separated relation. Fig. 4 is a 35 horizontal sectional view taken on the line 4—4 of Fig. 3. Fig. 5 is a sectional view taken on the line 5—5 of Fig. 3. Fig. 6 is a detail sectional view on the line 6—6 of Fig. 4. Fig. 7 is a perspective view of one 40 of the coupler heads.

In the specific embodiment of the invention as illustrated herein, a pair of frames 1 and 2 are shown, one of each being connected to the separate cars to be connected. These frames each comprise the skeleton side plates 3 joined together at their rear ends by the cross bars 4 and at their forward ends by cross bars 5. In the center of these frames, there is connected to the rear vertical members and the skeleton frame 3 by means of joints 6 the guiding arms 7 which are adapted to slide in ways 8 which are secured to the sides of the head mounting frames 9. These head mounting frames are 55 constructed in a similar manner to the

frames 1 and 2, that is, they are provided with skeleton side plates 10 which are connected together by the bolts 11 at both their forward and rear ends. The guiding arms 7 and the ways 8 pass loosely through 60 brackets 12 and are held against the side frames 3 normally by means of leaf springs 13 which bear against the inner face of the outer portion of the brackets 12 and are carried by the guiding arms 7. Each side 65 plate 10 of the frames 9 is provided with a lateral ear 14 to which one end of a spiral spring 15 is connected, the opposite end of the spring being connected to an ear 16 formed on the outer end of the guiding arms 70 7. By this it will be seen that the frames 9 are normally forced away from the frames 1 or 2 and when pressure is applied to the frames 9, as will be hereinafter described, the frames 1 and 9 may approach each other, 75 as will be readily understood, so that the frames may approach and move away from each other, as do the cars in travel. Any lateral movement or relative change in lateral position of the cars is taken up 80 through the springs 13 and the universal movement of the guide arms 7 at the joint 6. Any relative vertical difference in movement of the cars is taken up by the joint 6 and by the connection of the ways and arm 85 in the bracket 12 in which these parts are free to move vertically for considerable distance. The guiding arms 7 pass through guides 7^a secured to the side plates 10, the lugs 16 on said arms engaging the guides to 90 limit the relative separation of the frames 1 and 9, and 2 and 9.

The steam, air and signal pipes 17, 18 and 19, respectively, are shown mounted between and held in position by lateral grooved lugs 95 19^a projecting from the side plates of the frame 1 and a similar arrangement is observed in the frame 2 but not shown therein. These pipes terminate a little beyond the cross bars in depending nipples 21 and 100 connected to pipes 22, 23, and 24, by flexible tubes 25. The pipes 22, 23 and 24 are all rigidly held grooved in the lateral lugs 25^a forming a part of the frame 9 and each is provided with a lateral head 26 in which 105 the L-extension 27 of the coupler element 28 is journaled. The head 26 and the L-extension are provided with registering apertures which in the uncoupled position are out of register so that when the coupling elements 110

of separate cars are uncoupled, the connection between the head and L-extension will be disrupted. Each coupling element is provided with the central aperture and substantially circular body 29 which is connected to the head 26 by a spiral spring 30 so that the elements 28 are normally raised against a stop 30^a, so as to throw the apertures in the head 26 and the L-extension 27 out of register. Each element has a return hook formed thereon, shown at 31, and provided with an arcuate shoulder 32 against which the opposite element is adapted to abut. The underneath side of the hook is provided with a cam surface 33 over which an arcuate projection 34 is adapted to wipe. Each element is provided with one of these projections which is adapted to engage the cam surface of the opposite hook and each element is also provided with a stop in the form of a rod 35 which extends over the body of the element across the intervening space to be engaged by the hook. Each element as they approach each other abuts the arcuate shoulder upon the hook of the opposite element and as their bodies turn upon the shoulders and the L-extensions turn in the heads 26, the elements 28 are depressed to the position shown in Fig. 1, the arcuate projections 34 wipe upon the cam surfaces 33, draw the elements together with their central apertures registering. As the elements 28 are depressed the apertures in the L-extension and the heads 26 are brought into register so that the cars have their steam, air, and signal systems connected.

In order to guide the coupling elements of the separate cars into engagement with each other and the frames 9 into engagement, the frames are provided with a plurality of alternately arranged short and long fingers 36 and 37, respectively which have their outer ends inwardly and outwardly turned in order of their numbers and which coöperate the similar fingers on opposite sides of the opposite frame. For instance, the short fingers 36 of the left hand frame coöperate with the long fingers 37 on the opposite

frame, while the long finger 37 which lies in the same plane with the short finger 36 co-
operates with a short finger on the opposite frame, as shown. Projecting laterally from the frames 9 of the opposite cars are stop members 38 and 39 which abut each other when the frames are brought together and the fingers are in engagement so as to relieve the strain upon the pins 35.

What is claimed is:—

1. In a mechanism of the class described, the combination with mounting devices adapted to be secured upon the opposite cars to be connected, frames connected to said mounting devices for vertical and lateral movement, means for holding the frames normally in coupling position, a plurality of train pipes secured to the frames, coupling elements carried by the frames and having a valved and pivoted connection with said pipes and means to interengage the elements and the frames of the separate cars.

2. In a mechanism of the class described, the combination with supporting devices, frames slidably mounted on and connected to the supporting devices, for vertical and lateral movement, means for holding the frames resiliently separated from the supporting devices, a plurality of coupler elements carried by the frames, a plurality of train pipes secured to the mounting devices, valved and pivoted connections between the pipes and the coupler elements, means to interengage the frames of the separate cars, means to connect the coupler elements of the separate cars when the frames are interengaged, and means to operate the coupler elements to close the valves when the frames are disconnected.

In testimony whereof, I affix my signature in the presence of two witnesses.

MRS. GATSIE H. WIDDERS,
Widow of William D. Widders, deceased.
